UNITED STATES PATENT OFFICE.

EDWARD WILLIAM LLOYD, OF NEWCASTLE-UPON-TYNE, ENGLAND, AS
SIGNOR TO SIR W. G. ARMSTRONG, WHITWORTH AND COMPANY,
LIMITED, OF NEWCASTLE-UPON-TYNE, ENGLAND.

GUN-SIGHTING APPARATUS.

SPECIFICATION forming part of Letters Patent No. 687,324, dated November 26, 1901.

Application filed April 9, 1901. Serial No. 55,062. (No model.)

To all whom it may concern:

Be it known that I, EDWARD WILLIAM LLOYD, late commander Royal Navy, a subject of the King of Great Britain, residing at 5 Elswick Works, Newcastle-upon-Tyne, England, have invented a certain new and useful Gun-Sighting Apparatus for Practice Purposes, of which the following is a specification.

The object of this invention is to provide a 10 moving target at which gunners may practice the aiming of ordnance without actual firing thereof and also a means of recording the alinement of the gun at the instant when the trigger is pulled.

15 The apparatus consists of a miniature target placed a short distance in front of the gun and capable of being moved in any direction by hand and a paper or diagram holder which moves with the target and which is 20 marked at the moment the electric circuit of the gun-firing mechanism is closed by a pencil or the like fixed to and moving with the gun.

Figure 1 is a side elevation, Fig. 2 a front 25 elevation, and Fig. 3 a section on the line 3 3, Fig. 2, of an apparatus constructed according to this invention. Fig. 4 is a plan, and Fig. 5 a side elevation, showing in diagram the manner in which the apparatus is connected 30 to the gun.

The target *a* consists of a plate mounted on a bar *b*, along which it can slide for horizontal movement, while the bar can slide up and down in the frame *c*. The horizontal movement is given by a cord *d*, fixed at *a'* to the target, which moves it against a spring *e*, so that when the cord is let go the target is pulled back by this spring. Pulleys *f* may be employed, as shown, for the purpose of reducing the extension of the spring *e*.

The target is operated vertically by means of endless chains *g*, connected at *g'* to the bar *b* and driven by a handle *h*. The speed in this case also may be reduced by gearing, 45 as shown.

The marking mechanism consists of an electromagnet *j* in circuit with the firing-pistol or other firing mechanism of the gun, so that when the operator chooses to fire electric connection is made and the magnet attracts its

armature *j'*, forcing a pencil or other marker *k*, carried by the lever *l*, pivoted at *l'*, forward against a sheet of paper moving with the target, thus recording the direction of the gun when it was fired. In the arrangement 55 shown the target *a* itself forms the diagram-carrier; but they may be separate so long as they move together. It is indeed preferable that the diagram and pencil should be out of sight of the gunner. Immediately after firing 60 the armature *j'* is liberated and a spring *j''* brings it back into its normal position. The magnet *j* is mounted on a slide *m*, free to move horizontally along the bar *n*, which itself can move up and down in the frame *c*. 65

m' represents lugs on the slide *m*, by which it can be secured to the muzzle of the gun. This is done by means of a plug or tampion *p*, Fig. 4, fitting tightly into the muzzle of the gun and carrying an arm *q*, to which are 70 fixed two forks *r* to receive the lugs *m'*.

To avoid confusion, the parts are shown in Figs. 1 to 3 of the drawings in a position corresponding to a bad aim, and if the trigger were pulled when the parts were in this position the gunner would score a miss, for no mark would be made on the target *a*, because the pencil is not then in reach of it. When, however, the trigger is pulled at the proper time to score a hit, the pencil will make a 80 mark on the target—that is to say, when the parts are in the position shown in Figs. 4 and 5.

What I claim is—

1. The combination of a target, means for moving the same, a marker, means for connecting the marker to the gun, and an electromagnet operating the marker. 85

2. The combination of a target, means for moving the target in a horizontal direction, means for moving the target in a vertical direction, a marker, means for connecting the marker to the gun, and an electromagnet operating the marker. 90

3. The combination of a frame, a bar free to slide vertically in the frame, an endless chain fixed to the bar, a chain-wheel operating the chain, a target free to slide along the bar, a spring tending to draw the target in one direction along the bar, a cord fixed to 95 100

the target and by which it can be drawn in the other direction, a marker, means for operating the marker, and means for connecting the marker to the gun.

5 4. The combination of a frame, a bar free to slide vertically in the frame, an endless chain fixed to the bar, a chain-wheel operating the chain, a target free to slide along the bar, a second bar free to slide vertically in

the frame, a slide free to move along the second bar, means for connecting the slide to the gun, a marker carried by the slide and an electromagnet carried by the slide and operating the marker.

EDWARD WILLIAM LLOYD.
